CLAIM

The ornamental design for a medical equipment console as shown and described.

DESCRIPTION

The patent or application file contains at least one drawing executed in color. Copies of this patent or patent application publication with color drawing(s) will be provided by the Office upon request and payment of the necessary fee.

1. Medical equipment console

Fig. 1.1 is a front, left, and top perspective view of a medical equipment console showing my new design;

Fig. 1.2 is a front elevation view thereof;

Fig. 1.3 is a back elevation view thereof;

Fig. 1.4 is a left-side view thereof;

Fig. 1.5 is a right-side view thereof;

(Continued)

Fig. 1.6 is a top plan view thereof; and
Fig. 1.7 is a bottom plan view thereof.

The white color in the figures forms no part of the claimed
design.

**1 Claim, 7 Drawing Sheets
(7 of 7 Drawing Sheet(s) Filed in Color)**
